UNITED STATES PATENT OFFICE

HERMAN E. SCHULZE, OF NEW YORK, N. Y., ASSIGNOR TO H. E. SCHULZE INC., A CORPORATION OF NEW YORK

SHOE SHINING INSTALLATION AND THE ELEMENTS THEREOF

Application filed January 17, 1927. Serial No. 181,487.

My present invention is concerned primarily with installations and equipment for shoe polishing, although many of the features of the invention are applicable to other uses.

It is among the objects of the invention to provide equipment of the above type, by which shoes may be rapidly polished to a higher and more permanent polish, than was practicable heretofore, yet requiring only a small fraction of the time consumed by hand polishing, and requiring no muscular effort on the part of the operator.

Another object is to provide power driven equipment of the type mentioned, which is of small bulk, yet so rugged as to withstand, without danger of derangement, the hard usage to which it may be subjected by mechanically unskilled operators and which, in fact, is substantially fool-proof.

Another object is to provide shoe shining equipment of the type noted dispensing with the menial labor of a boot black and rendering the operation a clean and substantially effortless one.

Another object is to provide shoe shining equipment of the type noted, in which the danger is obviated, of catching and snapping the shoe laces or other dangling portions of the garments of the customer, and in which there is no danger of the polish becoming splashed in operation of the mechanical parts.

Another object is to provide an installation of the type noted in which the brushes may be readily interchanged in accordance with requirements.

Another object is to provide an installation of the type noted readily constructed at small expense from parts either of standard construction or readily made from standard stock.

Another object is to provide a shoe polishing implement of the character noted in which the brush automatically adjusts itself for efficient application to the surface being polished and in which overloading the driving motor by too suddenly applying the load thereto is effectively prevented.

Another object is to provide an installation which can be comfortably mounted by the patron without the need for stepping over foot rests, polish bottles and rags, which avoids excessive exposure to the view of the boot black or passers-by, which affords comfort to the patron, and inherently straightens out the creases in the vamp of the shoe while being polished.

In the accompanying drawings in which is shown one or more of various possible embodiments of the several features of this invention.

Fig. 1 is a side view partly in section showing a complete installation in use.

Fig. 2 is a fragmentary view in longitudinal cross-section of the flexible driving shaft and its brush.

Fig. 3 is a fragmentary detail on a larger scale of the resilient belt coupling.

Fig. 4 is a detail of the flexible shaft.

Fig. 5 is a transverse sectional view on a larger scale showing the brush, its handle and associated structure.

Fig. 6 is a view similar to Fig. 5 showing the mounting end of the flexible driving shaft, and;

Fig. 7 is a perspective view of a modification of the operator's seat.

Referring now to the drawings and more particularly to Fig. 1 thereof, I have shown an installation comprising a customer's seating unit A including a platform 10, a seat 11 and foot rests 12, and preferably a separate and distinct operator's unit B including a stool 13, a rotary brush 14 and a flexible driving shaft 15 through which the brush is rotated from an appropriate source of power, the operator holding the brush by a handle 16 at the outer end of the flexible shaft.

These constituent elements will now be separately described.

The customer's seating unit

This unit comprises a low platform 10 near the rear of which is mounted the stool including preferably a vertical hollow metal post 17 having the metal disk 18 at the top thereof, which carries the wooden seat 11.

The post is secured to the base, preferably by means of an ornamental nut 20, threaded upon the post, formed as a stool base and tightened against the platform 10 by a nut 21, threaded upon the lower extremity of the post and against the lower face of the platform.

At the front of the platform are mounted a pair of brackets 22, each carrying an upward standing rod 23 to the top of each of which is secured a foot rest 12. The foot rest is preferably fixed, but instead of tilting upward, as is usual, it is tilted downward through an angle preferably of approximately 20 degrees. By this arrangement, the tendency of the shoe vamp to curl upward and to afford transverse creases not accessible either to the dauber or to the polisher, is overcome. The vamp will naturally straighten as the sole of the user is tilted downward to press upon the full area of the foot rest.

In order to afford added comfort to the user while bringing the sole of the shoe into face contact with the downwardly inclined foot rests, I provide a convenient handle. This handle is preferably a hand rail 25, supported upon a pair of uprights 26 near the front of the platform, said uprights being secured in position upon the platform, preferably by an arrangement of nuts similar to that described in connection with the seat. Thus, the user while adjusting his feet upon the foot rests, would grasp the hand rail until comfortable.

The uprights and hand rail also lend themselves readily to the mounting thereat of a shield 27, especially desirable in view of the modern vogue of short skirts. The upper part of the shield is preferably curved outward and downward from the hand rail, as shown, and the lower part thereof extends vertically downward. The shield has lateral wings 28 which are secured into a unitary structure therewith by means of angle straps (not shown). The straight inner ends of the wings are secured to the uprights 26 by screws 30 extending through the narrow edge flanges 31 thereof. The lower edge of the shield preferably extends but little below the seat and almost directly above the forward ends of the foot rests, as will appear clearly from Fig. 1. Ample room is thus afforded for the knees of even a tall person.

Preferably an electric lamp L similar to those employed in show windows is mounted near the lower edge of shield 27 and serves to illuminate the shoes supported on foot rests 12.

While I have shown in the drawings but a single one of the customers' seats, it will be understood that these seats would preferably be arranged one next to the other on a single platform.

The installation is mounted by the customer stepping thereon from the side or the rear. Thus, there is avoided the discomfort of stepping over foot rests, bottles and rags. In fact, my device is not accessible for mounting from the front, since the hand rail frame 26-25 and the shield 27 are in the way.

The operator's unit

This unit preferably comprises a four legged stool 13 having a wooden seat 45 and provided with rubber casters 46 to assure insulation. Under the seat, there is mounted a suitable electric motor 47 which is preferably of only one-fourth horse power. The motor may be energized from a wall outlet 48, as shown, by the insertion of a terminal plug 49 at the end of the flexible motor conduits 50. A small rotary snap switch 51 controls the motor circuit and is disposed directly under the seat and at the forward end thereof, by which the operator can readily open and close the motor circuit, without rising from or turning on his stool or reaching out. Between the two forward legs of the stool is disposed a metal panel 52, through which extends a fixed bearing bushing 53 provided with an inner flange 54 clamped against the metal of the panel by a nut 55 threaded upon the exterior part of the bushing and having a large face 56 against panel 52. Within the bushing is mounted a mechanical terminal in the form of a bearing stub shaft 57, the outer end of which has a stop shoulder 58, and upon the inner end of which is secured as by a set screw 59, the hub of a driven pulley 60. The motor shaft has a smaller driving pulley 61 and the torque is transmitted from the motor to the driven pulley preferably by a resilient belt 62, the purpose of which will appear more fully hereinafter.

Since my resilient belt per se is not broadly new, I will briefly state that it comprises a closely wound coil spring 63. The ends of the spring are connected together to form an endless belt, preferably by means of a short length of coupling spring 64, of diameter somewhat smaller than that of the spring 63, so as to be readily threaded by a screwing action partway into one end of the spring, whereupon the opposite end of spring 63 is threaded upon the protruding end of the coupling spring. The belt is preferably mounted to exert a substantial resilient pressure upon the pulleys.

Preferably the bushing 53 is mounted under the stool so as to tilt slightly upward, as shown, for a purpose which will appear hereinafter. To this end, the motor 47 is preferably mounted at a corresponding tilt, as shown in Fig. 1, by employing a wedge-shaped mounting base 65, so that the transmission belt 62 extends in proper relation in

end to coincide with a plane in a plane at right angles to the shafts between which it transmits torque.

Upon the outer end of the shaft stub 57 is mounted the flexible driving shaft 67. For this purpose, the extremity of said shaft has brazed thereonto a terminal socket 68 threaded upon a corresponding nipple 69 formed rigidly upon the end of the stub shaft 57. The opposite end of the flexible shaft 67

10 preferably extends and is brazed into a corresponding socket 70 in the extremity of a metal haft 71 upon which the rotary brush 14 is mounted. The brush and its specific mount will be described hereinafter.

15 In order to protect the flexible shaft from injury, I provide preferably an armor sheath 75 of helically wound interfolded sheet metal strip. In my construction, however, preferably the armor is formed of two telescoped 20 sheaths 75' and 75", the outer surface of the inner sheath affording a sliding bearing for the inner surface of the outer sheath.

The compound armor sheath is preferably 25 fixed at the stool end by brazing into a corresponding socket 76 of a terminal piece 77 therefor, which affords a passage 78 therethrough for the flexible shaft 67, said terminal piece being threaded at its extremity at 79 upon the bearing bushing 53.

30 The opposite end of the armor sheath has preferably secured thereto a sleeve 80 which encircles and affords a running bearing for the haft 71 and also serves as a handle grasped by the operator in use.

35 Preferably the sleeve 80 is of composite construction including a collar 81 to which the outer end of the armor 75 is brazed, a section 80 of greater length serving as the bearing for the haft and being threaded at 82 into collar 81. A non-metallic handle sleeve 83 encircles the sleeve 80 and is retained in position by a nut 84 pressing the opposite end of said sleeve against collar 81. The nut 84 has an integral collar ring 85 for purposes 45 which will appear hereinafter.

The rotary brush comprises a hollow core 86 into which the brush tufts 14 are secured preferably by metal stitching (not shown) which in itself is not my invention. A hub sleeve 87 extends through the core 86 and has an overturned end 88 reacting against an end disk 89 and is secured in position by a nut 90 threaded upon the opposite end thereof and reacting against a disk 91.

55 In a preferred embodiment, the brush is driven from the flexible shaft 67 through a resilient element. This element preferably comprises a helical coil spring 92 of substantial length extending through the entire 60 length of the hub 87 and protruding therebeyond as at 93. Illustratively, the extremity of said spring may be brazed into a coupling sleeve 94, the opposite end of which encircles the extremity of the haft 71 and is secured thereto by means of a set screw 95.

The free extremity of the spring 92 has a metal plug 96 brazed thereto, provided with a threaded nipple 97 over which the correspondingly tapped extremity 98 of the hub sleeve 87 is threaded to mount the brush. The sleeve 80 is preferably of brass, and as shown, affords a thrust bearing 99 at its extremity for the end of the coupling collar 94.

It will thus be seen that the flexible shaft 75 has a bearing support 53 for its stub shaft at the driving end, a bearing support 80 for its haft 71 at the opposite end and a thrust bearing 99 for the extremity of the coupling, 80 mounting the brush. The flexible shaft 67 has a relatively fixed attachment only at the stool, so that when the handle is held downward the weight of the brush is suspended from the bearing 53 through the length of flexible shaft 67.

In use, the operator seated on his stool, having daubed the shoe, simply turns the switch button 51 under the seat, whereupon the brush will revolve. The speed of revolution of the brush with the arrangement disclosed, may be as low as 360 P. M., an electric motor of say 1400 P. M., being correspondingly stepped down by selecting pulleys 60 and 61 of appropriate diameters, although speeds considerably higher may be 95 used to advantage. The operator gently holds the brush against the shoe, while passing it over the surface thereof. In practice, it is neither necessary nor desirable to exert any substantial pressure through the brush.

In a maximum of a minute to 90 seconds, the shoes become highly polished. I have discovered that this operation produces a higher and more permanent polish than results from more intense pressure. If, however, the operator should press hard upon the shoe, no 100 injury will result from overloading the motor because the helical driving spring 92 through

which the torque from the flexible shaft 67 is transmitted to the brush, will yield laterally and thereby assure a gradual application of the load to the motor. No particular skill is required by my arrangement in order to dispose the brush in most effective position relative to the shoe. Regardless at what angle the brush handle be held, the helical spring will yield laterally so that the elements of the cylindrical brush will contact the shoe substantially throughout the length thereof.

115 My arrangement of brush and driving means is essentially a fool-proof one, which will withstand substantially all kinds of rough usage. The brush will operate effectively even though the armor sheath 75 with its enclosed flexible driving shaft 67 be tied into a loop. If an excessive load is applied to the brush, no injury results to the 120 motor. The fuse does not burn out, but 125

what happens in that contingency is that the flexible or resilient driving belt 62 slips at one or both of the pulleys 60, 61.

My tests have shown that with a single 5 armor sheath, a substantial kink or bend may result in rupture. By providing the double sheath armor, as set forth, I have produced a construction of durability, far more than doubled. Apparently, each of the sheaths 10 affords a sliding bearing for the other and when the hose is held in the hand and bent, the sliding displacement of the outer sheath along the surface of the inner is readily felt.

The disk or collar ring 85 serves as a rest 15 for the hand in use. Moreover, when it is desired to lay down the brush, when still spinning, the handle member is merely laid crossways upon the terminal piece 77, as best shown in Fig. 3. The terminal being inclined 20 downward toward the metal panel 52, it will be seen that the handle 83 tends to slide toward the panel, and the end disk 85 sustains the brush from being drawn off by the weight of the depending flexible shaft and armor 25 sheath 75.

The various threaded connections afforded in my driving transmission, including that at the driving stub shaft at 78, and the thread 97 securing the brush 14 are preferably right- 30 hand threads, opposite to the direction of rotation of the flexible driving shaft 67. Thus, obviously, the tendency of the rotating mechanism is to tighten rather than to loosen these threads, which threads, therefore, need not 35 be and preferably are not locked. This arrangement, it will be seen, affords great convenience for replacing a black brush, say with a tan one, in the course of ordinary use of the equipment. All that is necessary to do 40 is for the operator to revolve the brush upon its handle in clockwise direction by hand and draw it off, slipping the substitute brush thereover, and without any further operation, as soon as he holds the brush against the 45 shoe, the thread is automatically closed and remains secure throughout use.

While the inner flexible driving shaft may be made according to familiar practice, a most durable and desirable shaft is provided 50 by forming the same from a single length of steel frame wire, drawing said wire back and forth in preferably eight or nine longitudinal strands 100, and then tightly winding the remaining length of wire about said 55 strands as a core with the convolutions 101 in close contiguity to each other. Thereby is provided a self-contained unit length of flexible shaft for my purpose, to one end of which would be brazed the socket terminal 60 and to the other end the shaft terminal. The brazed ends prevent separation or loosening of the convolutions or spreading of the core strands, which might occur when 65 lengths of flexible shaft are severed for use, from a reel.

In Fig. 7 is shown a modification of the portable boot black's stool, more especially useful in barber shops, where patrons have their shoes shined while receiving torsional treatment in fixed barber chairs. The unit 7 described comprises the usual base or chassis 110 with wheels 111 upon the rear part of which is mounted a stool 112, preferably of construction similar to or identical with that shown in Fig. 1 and above described. From the forward end of the stool protrudes the terminal piece 113 from which extends the flexible shaft 114 at the outer end of which is mounted the rotary brush 115, all as in the embodiment of Fig. 1. At the forward end of the chassis, is a steering wheel 116, the mounting clevis 117 of which is fixed to an upstanding post 118 rotatably mounted in bearing 119 and carrying the foot rest 120 at its upper end. It will be understood that the outlet at the end of the flexible conduits 121 of the motor 122 will be plugged in by the boot black at one of the outlet boxes used by the barber for operating his electrical equipment, and the mode of use of the installation will be apparent from the previous description.

It will thus be seen that there is herein described apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawings shall be interpreted as illustrative and not in a limiting sense.

Having thus described my invention, what I claim as new and desire to secure by Letters-Patent is:

1. A power driven brush, having a drive shaft including a laterally yielding resilient torque transmitting member at the outer end of said drive shaft, a brush having a hub encircling said resilient member, extending substantially the length thereof and affixed to the outer or free end thereof, and a handle adjacent said brush through which said drive shaft extends.

2. A power driven brush comprising a transmission shaft, a helical coil spring affixed to the outer end of said shaft, a rotary brush having a hub encircling said coil spring, means securing said brush to the outer end of said coil spring and a handle sleeve for said brush encircling said transmission shaft and affixed adjacent said brush.

3. A power driven rotary brush, having a hollow hub, a power transmission shaft including a coil spring extending through said

brush hub and substantially the entire length thereof, means affixing said brush at the outer end thereof to the outer end of said coil spring, a handle sleeve swivelled about said transmission shaft and means retaining said sleeve contiguous to said brush.

4. A power driven rotary brush having a hollow hub, a helical torsion spring extending through said hub and the entire length thereof, a power transmitting shaft having fixed to the outer end thereof the inner end of said spring, a part of the length of said driving spring protruding between the spring end of said shaft and the end of the brush hub, means securing the outer end of the helical spring rigidly to the outer end of the brush hub, and a handle sleeve having a swivelling mount upon said rotary shaft adjacent said brush.

5. In apparatus of the character described a rotary brush having a hollow hub, a power transmitting shaft, a helical driving spring secured to the outer end of said shaft and extending through said brush substantially the entire length of the hub thereof, said helical spring having a threaded nipple at the outer end thereof, said brush hub having a nut threaded upon said nipple in direction opposite to that in which the power is applied in use of the brush.

6. A rotary brush unit comprising a hollow hub having a nut at one end thereof, a helical coil spring of diameter nearly equal to the bore of said hub and having a threaded nipple at the outer end thereof for coaction releasably with said nut, said helical coil spring protruding beyond the opposite end of said hub for engagement with a rotary power shaft.

7. In apparatus of the character described a flexible driving shaft, a rigid haft secured to the end of said shaft, a rotary implement, a resilient transmission member secured to said implement, and at one end to the outer end of said haft, and a handle sleeve for said implement having a swivelling connection about said haft.

8. In apparatus of the character described a flexible driving shaft, a rigid shaft secured to the end of said shaft, a rotary implement having a hollow hub, a resilient transmission member secured at one end to said rigid shaft extending through said hollow hub and secured to said hub at the other end thereof, and a handle sleeve having a swivelling connection about said rigid shaft.

9. In a power driven hand controlled tool, a flexible driving shaft, an elongated helical driving spring yieldable transversely and secured at one end to the outer end of said flexible shaft, said tool having a hollow hub encircling said helical spring, means attaching the outer end of said spring to said hub and a handle sleeve encircling said flexible transmission end, having a swivel connection

thereabout and fixed against longitudinal displacement with respect to said tool.

10. In a power driven shoe shining device, the combination of a flexible driving shaft, a rigid shaft affixed to the outer end thereof, an elongated helical coil spring affixed at one end to the outer part of said rigid shaft, a rotary brush having a hollow hub encircling said coil spring with small clearance, means securing the outer end of said hub to the outer end of said spring, a short part of the length of said spring being exposed between the rigid shaft and the contiguous end of the hub, and a hollow handle sleeve encircling said rigid shaft, limited against displacement longitudinally thereof and permitting free rotation of said shaft therein.

11. A power driven shoe shining device including a flexible driving shaft, a haft into one end of which the extremity of said driving shaft is secured, a coupling sleeve attached to the other end of said haft, a helical coil driving spring affixed at one end to said coupling sleeve, a rotary brush having a hollow hub encircling said coil spring, means detachably securing the outer end of said hub to the outer end of said coil spring, a handle sleeve encircling said haft and means limiting longitudinal displacement of said handle sleeve.

Signed at New York in the county of New York and State of New York this 15 day of January, A. D. 1927.
